UNITED STATES PATENT OFFICE.

FREDERICK NEWHOUSE, OF TOLEDO, OHIO, ASSIGNOR OF ONE-HALF TO
E. J. AND F. L. CABLE, OF SAME PLACE.

LOCOMOTIVE.

SPECIFICATION forming part of Letters Patent No. 311,601, dated February 3, 1885.

Application filed October 20, 1884. (No model.)

To all whom it may concern:

Be it known that I, FREDERICK NEWHOUSE, a citizen of the United States, residing at Toledo, in the county of Lucas and State of Ohio, 5 have invented a new and useful Improvement in Locomotive-Power-Increasing Devices, of which the following is a specification, reference being had to the accompanying drawings.

My invention relates to a speed-increasing device for locomotives; and it has for its object to provide a device of this character which shall be simple in its construction, effective in its operation, one that may be easily applied, and one that will be strong and durable.

15 With these ends in view the invention consists in so connecting the locomotive and tender that when the same are in motion the tender will be raised sufficiently to throw a portion of its weight upon the engine, and thus increase the friction of the driving-wheels thereof and prevent any slipping of the same.

The invention further consists in the details of construction and combinations of parts, hereinafter fully described, and pointed out 20 in the claims.

In the drawings, Figure 1 is a side elevation of a locomotive and tender, showing my improved means for connecting the same. Fig. 2 is a vertical section, and Fig. 3 is a horizontal section.

30 In the accompanying drawings, in which like letters of reference indicate corresponding parts in all the figures, A represents the locomotive, and B the tender.

Upon the rear end of the locomotive, at or 35 about the point usually occupied by a draw-head, are provided two outwardly-extending lugs, C, between which is pivoted a draw-bar, D, by means of a bolt, a, passing through openings in said lugs.

Upon the under side of the tender, at the forward end thereof, are provided two downwardly-extending plates or bars, E, said bars or plates being located upon opposite sides and 45 at equal distances from a point midway between the sides of the tender. The plates or bars E are segmental in form, and are provided with slots b, running nearly their entire length.

50 Extending outwardly from the forward ends

of the slotted plates or bars E are flanges F, having gear-teeth, as shown.

G represents a shaft which is mounted in the slots of the plates E. This shaft has hand-wheels c at its ends, and is provided with pinion-wheels H, which are rigid upon said shaft. These wheels, which are located outside of the segmental plates E, are adapted to mesh or gear with the rack-flanges F. It will thus be seen that as the plates are segmental in form and have segmental slots, the shaft may be raised or lowered in said slots by turning either one of the hand-wheels, which causes the pinions to gear with the rack-teeth and the shaft to be raised or lowered, according to the direction in which said hand-wheel is turned. Moreover, said shaft will be held in the position to which it is adjusted. The end of the link or draw-bar D has an elongated slot, e, to receive the shaft G, thus connecting the engine and tender. It will thus be seen that in stopping the train the bar D will not be subjected to any strain, or is not likely to be broken. Chains I may be secured to the lower ends of the rack-plates and to the beams upon the under side of the tender, and in this manner relieve said plates of a portion of the strain and prevent them from becoming broken.

The operation: When it is desired to increase the friction of the driving-wheels, the shaft G 80 is turned by one of the hand-wheels in a direction so that the said shaft will be lowered by the gears thereon meshing with the rack-flanges. By thus lowering the shaft the locomotive is made to support a portion of the 85 weight of the tender, thus increasing the friction of the driving-wheels. When it is desired to remove the weight of the tender from the engine, the shaft is moved to the upper ends of the slots in the rack-plates, thus removing the weight from the locomotive.

The device above described is simple in its construction, may be readily applied, is effective in its operation, and strong and durable.

Having fully described my invention, what I claim as new, and desire to secure by Letters Patent, is—

1. The combination, with a locomotive and tender, of a vertically-adjustable shaft mount-

- ed upon the under side of the tender, a bar connecting said shaft and the locomotive, and means for raising said shaft and bar, as set forth.
5. 2. The combination, with a locomotive and tender, of a vertically-adjustable shaft mounted upon the under side of said tender, a bar having an elongated slot, and means for raising said shaft and bar, as set forth.
10. 3. The combination, with a tender, of downwardly-extending slotted plates, a shaft mounted therein, and a bar connecting said shaft and the locomotive, substantially as set forth.
4. The combination, with a tender, of downwardly-extending slotted segmental plates, a shaft mounted in said slots, and a bar connecting said shaft and the locomotive, as set forth.
15. 5. The combination, with a tender, of down-
- wardly-extending slotted segmental plates, a shaft mounted in said slots, a bar having an elongated slot and connecting said shaft and the locomotive, substantially as set forth.
6. The combination, with a tender, of downwardly-extending slotted segmental plates secured to the underside thereof, outwardly-extending rack-flanges formed integral with said plates, a shaft mounted in said slots, pinions on said shaft, and a bar having an elongated slot, as set forth.

In testimony that I claim the foregoing as my own I have hereto affixed my signature in presence of two witnesses.

FREDERICK NEWHOUSE.
